UNITED STATES PATENT OFFICE.

BERG HEINRICH, OF ANDERSON, INDIANA, ASSIGNEE TO MID-WEST BOX COMPANY,
OF ANDERSON, INDIANA, A CORPORATION OF INDIANA.

MACHINE FOR SEALING BOXES

1,393,122.

Specification of Letters Patent. Patented Oct. 11, 1921.

Application filed October 6, 1920. Serial No. 415,077.

To all whom it may concern:

Be it known that I, BERG HEINRICH, a citizen of the United States, and a resident of Anderson, in the county of Madison and 5 State of Indiana, have invented certain new and useful Improvements in Machines for Sealing Boxes, of which the following is a full, clear, and exact description.

The invention relates to machines for sealing boxes and its object is to provide a machine in which one of the press members is operable vertically and laterally for convenience in manipulating the box onto and off the coacting press member and while it is 10 on one of the press members. Another object of the invention is to provide improved means for effecting adjustment of one of the press members relatively to the other to adapt them for sealing boxes of different 15 sizes.

The invention consists in the several novel features hereinafter set forth and more particularly defined by claims at the conclusion hereof.

25 In the drawings: Figure 1 is a vertical section of a machine embodying the invention. Fig. 2 is a plan.

The invention is illustrated in a machine comprising a rotatable series of presses each 30 adapted to hold a box while it is being sealed. A standard 6 is rotatably held in a stationary base 7 and is adapted to support the series of presses. Each press comprises a lower member 8 and a coacting upper member 9 35 between which the box is adapted to be held while it is being sealed. Each member 8 is supported by a screw-threaded standard 10 which is held in a correspondingly threaded sleeve 11 which is secured in one of the arms 40 12 of the lower carrier 14. Each arm 12 is secured to the carrier 14 by bolts 13 and is secured to rotate with the standard 6 by a set screw 15. A wheel 17 is threaded to the standard 10 and is adapted to lock the latter 45 against rotation in the sleeve 11 and relatively to the carrier 14 and arms 12. The upper press members are supported from a carrier 21 which is rotatable with the standard 6. The latter is provided with a screw 50 thread 20 and the hub of carrier 21 is correspondingly threaded, so that the carrier and upper press members sustained thereby may be vertically adjusted by rotating the carrier on the standard. A wheel 19, which 55 is threaded conformably to screw-thread 20,

is adapted to lock the carrier so that the standard and carrier will rotate together. The standard may, if desired, be provided with a series of holes 23 adapted to receive a pin 22 which is adapted to pass through 60 the hub of carrier 21 to further lock together the carrier and standard. This construction exemplifies one in which the upper press members may be adjusted vertically relatively to the lower members by rotation 65 thereof around the supporting standard.

A supporting and operating connection between the carrier 21 and each of the press-members 9, so that these upper press members may be raised and lowered independently of one another and conjointly rotated with the carrier, is provided. Each of these connections comprises an arm 25 made up of a pair of bars 26 rigidly secured together in spaced relation by cross studs 27. The 70 inner end of each arm 25 is pivoted, as at 28, to an intermediate member 25' which is connected by a pivot pin 25^a so it may be swung laterally relatively to the carrier 21 and the coacting press-member 8. The hub 75 of member 25', through which the pivot pin 25^a extends, is confined between lugs 21' on the carrier 21, so that it will move vertically with the carrier. Each member 25' is provided with stop lugs 25^c adapted to strike 80 shoulders 25^d on carrier 21 to limit the lateral swing of member 25' and the parts sustained thereby. Press member 9 is suspended from a pin 30 which passes through the front ends of bars 26 which form the arm 25 and 85 through a socket 31 which is secured to the top of said member. Pin 30 passes through a collar 33 and slots 34 in socket 31 and a spring 35 is interposed between collar 33 and the socket, so that yielding pressure will 90 be applied to member 9. This connection permits the presser-head to accommodate itself to any inconvenience or irregularity in the box. Normally, the arm 25 is held in raised position by a spring 36 which is connected to said arm, as at 37, and to the member 25', as at 38. The supporting arm 25 is adapted to swing about its pivot 28 to raise and lower member 9 by a self-locking linkage comprising a pair of toggle links 39 95 and 40 pivoted to each other at 41 and to arm 25 at 42 and to member 25' at 43 respectively. A lever 44 has its inner end fulcrumed upon the pin 30 and has a handle 45 at its outer end. An operating rod 46 is 100 105 110

2
pivoted to lever 45 by a pin 47 and pivoted to the connecting pivot 41 between the toggle links. The latter are adapted to pass into dead center relation to constitute an automatically locking linkage whereby the arm 25 will be locked in position to hold the press member 9 against the box being sealed. Rod 46 is adapted to operate the toggle links from lever 44 to release the linkage and permit arm 25 to raise the press-member away from the box where it will be held by spring 36.

The operation of the machine will be as follows: The operator will place the box to be sealed upon the lower press member 8, said member having been first adjusted so it will operate upon such boxes. While the box is being placed on one of the lower press-members and its flaps are being folded into position for sealing, the coacting upper 20 press member 9 will be raised and also swung laterally as shown in Fig. 2. When this member is swung laterally, the manipulation of the box onto and while it is on the lower press member is facilitated. 25 When the box is ready to receive the pressure from the upper member 9, the operator will grasp handle 45 and swing the operating connection and arm 25 laterally until the member 9 carried thereby 30 will register with the box and will then pull lever 41 forwardly and downwardly until the rod 46 has operated the toggle links into self-locking position, whereupon, the press member 9 will exert the desired pressure 35 upon the box to seal it. After a box has been placed in one of the presses in this manner, the entire series of presses may be rotated to bring the next one into position to receive a box. While one of the presses is 40 being loaded, the others can remain operative to complete the sealing operation.

The invention exemplifies a box sealing machine in which one press member is supported so that it may be swung vertically 45 and laterally away from its coacting member or the box thereon.

The invention is not to be understood as restricted to the details set forth, since these may be modified within the scope of the appended claims, without departing from the spirit and scope of the invention.

Having thus described the invention, what I claim as new and desire to secure by Letters Patent, is:

55 1. In a box sealing machine, the combination of a pair of coacting press members, a support, a connection between one of the press members and said support which permits said member to move vertically and laterally relatively to the other member to provide free access thereto, and means for retaining the movable member in operative position.

60 2. In a box sealing machine, the combination of a pair of coacting upper and lower

press members, a support, a connection between the upper press member and said support, which permits said member to move vertically and laterally relatively to the lower member to provide free access thereto, and means for retaining the upper member in operative position.

3. In a box sealing machine, the combination of a pair of coacting upper and lower press members, a support, a connection between the upper press members and said support, comprising an intermediate member pivoted to swing laterally relatively to the support to provide free access to the lower member, an arm pivoted to said intermediate member to swing vertically, and means for securing the arm to hold the upper member in operative position.

4. In a box sealing machine, the combination of a pair of coacting upper and lower press-members, a support, a connection between one of the press-members and said support comprising an intermediate member free to swing laterally relatively to the support, an arm pivoted to said intermediate member to swing vertically and to the outer end of which one of the press-members is connected, and a lever pivotally connected to the arm and whereby the arm may be shifted.

5. In a box-sealing machine, the combination of a pair of coacting upper and lower press-members, a support, a connection between one of the press-members and said support comprising an intermediate member free to swing laterally relatively to the support, an arm pivoted to said intermediate member to swing vertically and to the outer end of which one of the press-members is connected, a locking connection between the intermediate member and the arm, and a lever pivoted to the arm and connected to the locking connection and whereby the arm may be shifted laterally and vertically.

6. In a box sealing machine, the combination of a series of rotatable presses each comprising a pair of coacting press members, means to support the members for conjoint rotation, connections for one member of each press whereby they may be swung individually vertically away from its coacting member and laterally to provide free access thereto, and means for securing said movable members in operative position.

7. In a box sealing machine, the combination of a series of presses conjointly revoluble each comprising a pair of coacting upper and lower members, and supporting means for the upper members comprising a carrier, connections between the upper members and said carrier which permit the upper members to be individually swung vertically and laterally relatively to its coacting member to provide free access thereto, and a carrier for the lower press-members.

8. In a box sealing machine, the combination of a series of conjointly revoluble presses each comprising a pair of coacting upper and lower members, supporting means comprising a carrier for the upper members and connections between the upper members and said carrier each comprising a member pivoted to the carrier to swing laterally, and an arm pivoted on said swinging member to swing vertically, and positive locking means between said arm and the swinging member.
- 5 9. In a box sealing machine, the combination of a rotatable standard, a press comprising a pair of coacting upper and lower members, a carrier for one of said members, a 15 screw-threaded connection between said carrier and said standard, said carrier being rotatable relatively to said standard so that it may be adjusted vertically by revolution of the carrier relatively to said standard, 20 and means for locking the carrier to the standard.

BERG HEINRICH'S.
